UNITED STATES PATENT OFFICE.

WALTER E. AMBERG, OF CHICAGO, ILLINOIS, ASSIGNOR TO CHICAGO STEEL POST CO., OF CHICAGO, ILLINOIS, A CORPORATION OF ILLINOIS.

METHOD OF ATTACHING FENCE WIRES.

1,278,413.

Specification of Letters Patent. Patented Sept. 10, 1918.

Original application filed September 8, 1916, Serial No. 118,984. Divided and this application filed June 21, 1917. Serial No. 176,035.

To all whom it may concern:

Be it known that I, WALTER E. AMBERG, a citizen of the United States, residing at Chicago, in the county of Cook and State of Illinois, have invented a certain new and useful Method of Attaching Fence-Wires, of which the following is a specification.

This invention relates to a process of attaching wire fencing and similar structure to its supporting means and is exemplified by the steps of the operation described in the following specification and illustrated in the accompanying drawing, and it is more particularly pointed out in the appended claims.

15 This application is a division of my prior application Serial No. 118,984 filed September 8th, 1916.

In the drawing, Figure 1 is a plan view and Fig. 2 a side elevation of one form of tool which may be used in carrying out the present invention; and Fig. 3 illustrates one manner in which the invention may be performed by the aid of the tool shown in Figs. 1 and 2.

20 In modern fence building metal posts made of angle bars of steel or iron have come into extensive use, but one difficulty has heretofore been experienced in connection with such posts and that is the difficulty of 25 securing the fencing to the post by an operation sufficiently simple to commend itself to fence builders. Previously, where wooden posts were used, it was only necessary to place a staple astride the wire and drive it 30 into place with a hammer. This is an operation which a single person can perform without any great difficulty and without previous training. It is, of course, impossible to fasten the wire to a metal post in 35

40 this manner and a great many attaching devices have been devised for use in connection with such posts the majority of which have required an elaborate operation to secure them in their connection with the 45 post and wire. In the present invention I employ the usual form of staple to which fence builders are accustomed and place it astride the wire in the manner used in connection with wooden posts. The metal post, 50

such as is shown at 1 in the drawing, is provided with an opening 2 through one of its webs which is preferably, although not necessarily, of an elongated shape. The wire 3 is brought opposite one of these openings and

the staple is then placed astride the wire 55 and its prongs 4 are inserted through the opening. To complete the process of securing the wire in place, I then preferably use a tool similar to that shown at 5 in the drawing having a handle 6 which is bent at 60 one end, as shown in Fig. 2 to form a U-shaped gripping portion 7. The gripping portion 7 is offset at one side of the handle 6 and the outer prong 8 of the U is rounded on its outer surface, as shown at 9 in Fig. 65 2. The end of the handle portion opposite the U-shaped gripping portion 7 may be wedge shaped as indicated at 10 for spreading the prongs 4 of the staple if this is found necessary, but ordinarily this is not required. 70 After the staple is in place with the prongs 4 protruding through the opening 2, the gripping portion 7 of the tool 5 is placed over one of the prongs 4, as shown in Fig. 3, 75 and the tool moved into the dotted position indicated in that figure. The curved portion 9 permits the tool to roll easily against the surface of the post into the position shown in broken lines. This movement bends the prong 4 of the staple into the shape of an arc and brings the point of the prong against the surface of the post opposite that to which the wire is being secured. After one of the prongs has been bent in the manner described, the tool is removed and applied 80 to the second prong which is then bent in a similar manner in the opposite direction. In applying the tool to the staple prong, the best results are obtained if it is not held too close to the post at the beginning of the 85 movement of the tool, in order that the staple may not be drawn so tightly against the wire as to prevent free movement of the wire through the staple during expansion and contraction. When both prongs of the 90 staple have been bent, the fastener will appear as indicated at the lower portion of Fig. 3. It will be noted that the sharp ends of the staple are both bent into contact with the surface of the post so that it is impossible for them to inflict injury on animals or persons. Where oblong openings are used the staple is prevented from rotating in the opening by the walls thereof. Where circular openings are employed the same result 100 is secured by the fact that the staple is placed astride of the fence wire. If the staple should rotate somewhat in its open-

ing, the ends of the prongs 4 will nevertheless continue to bear against the surface of the post and the function of the device will in no way be changed. If in any case it 5 happens that the prongs of the staple after being passed through the opening in the post are too close together to permit the easy operation of the tool, the prongs may be slightly spread before the head 7 of the 10 tool is applied to them.

It will be understood that although I have described the best method now known to me for carrying out my invention, the essential 15 features of the invention may be performed without following all the details included in this description.

The tool shown and described is a convenient one for performing the steps of this invention, but it will be readily understood 20 that other tools may be used for this purpose.

I claim:

1. The method of securing fencing to a support therefor which consists in passing 25 the prongs of a bifurcated staple astride a strand of said fencing and through an opening in said support, grasping the protruding ends of said prongs and bending said ends to 30 clench the same while maintaining tension thereon to hold the staple in place.

2. The method of securing fencing to a support which comprises placing an ordinary U-shaped staple astride a strand of wire, passing the prongs of said staple 35 through an opening in said support and bending the prongs of said staple backwardly upon themselves about a forming bar held between the portion of said staple being bent and the fence wire support.

40 3. The method of securing fencing to a support which comprises placing a U-shaped staple astride a strand of wire to be secured, passing the prongs of said staple through 45 an opening in said support for the said wire, successively engaging the projecting prongs of said staple between the sides of a bifur-

cated stapling tool and operating said tool to bend said prongs about a portion of said tool held between the prong being bent and the surface of said support to impart arc-shaped curves to said prongs and to bring the ends of said prongs into contact with the surface of said support opposite the wire engaging portion of said staple.

4. The process of securing fence wire to 55 a support therefor comprising the steps of engaging the wire by means of a securing device having a prong thereon, passing the prong through an opening in the support, grasping the portion of the prong extending 60 through said opening and bending said prong into a curved form to bring the end thereof adjacent the surface of said support opposite the wire engaging portion.

5. The process of securing fencing to a 65 support comprising the steps of engaging the fencing by means of a securing device having a prong thereon, passing the prong through an opening in said support, grasping the projecting portion of said prong and bending said portion about a member held between said prong and said support in a manner to exert tension on said prong tending 70 to draw it through said support.

6. The method of securing fencing to a 75 support therefor which consists in passing the prongs of a bifurcated staple astride a strand of said fencing and through an opening in said support, successively grasping the protruding ends of said prongs and 80 bending said ends about a spacing member held between said prongs and said support to bring the ends of said prongs into engagement with the face of said support so that the bending action will produce a tension upon said prongs to hold said staple 85 in position during the clenching operation.

In testimony whereof I have signed my name to this specification, on this 15th day of June, A. D. 1917.

WALTER E. AMBERG.
